UNITED STATES PATENT OFFICE.

KENZAEMON NISHIMOTO, OF OAKLAND, CALIFORNIA.

AUTOMATIC DOOR OPENER AND CLOSER.

No. 839,627.

Specification of Letters Patent.

Patented Dec. 25, 1906.

Application filed June 25, 1906. Serial No. 323,904.

To all whom it may concern:

Be it known that I, KENZAEMON NISHIMOTO, a citizen of Japan, residing at Oakland, in the county of Alameda and State of California, have invented new and useful Improvements in Automatic Door Openers and Closers, of which the following is a specification.

My invention relates to means for automatically opening and closing doors. Its object is to provide a means for automatically opening and closing doors which will combine the use of a spring-motor and an electric motor. The spring-motor is adapted to open the door or doors, and the electric motor is designed to reset the spring-motor in readiness for the next operation, one purpose of my invention being to save power by having the electric motor operate only at intervals when actually needed.

The invention consists of the parts and the construction and combination of parts, as hereinafter more fully described and claimed, having reference to the accompanying drawings, in which—

Figure 1 is a plan view of the operating mechanism of the invention with the platforms partially broken away and showing the spring-motor at the right in set operative position and with the motor on the left released to open the doors toward the right. Fig. 2 is a side elevation of the means for setting the motors. Fig. 3 is a side elevation of the clutch-operating mechanism. Fig. 4 is a side elevation of the mechanism for preventing the simultaneous depression of both platforms. Fig. 5 is a plan view of part of the mechanism shown in Fig. 4 with the latch in normal position. Fig. 6 is a view similar to Fig. 5, showing the latch engaged behind a block. Fig. 7 is an elevation of the clutch mechanism for operating the pinion. Fig. 8 is a section on line $x-x$, Fig. 7. Fig. 9 is a detail of the detent means for the spring-motor. Fig. 10 is an elevation of a part of the mechanism shown in Fig. 2. Fig. 11 is a plan view of the mechanism shown in Fig. 10. Fig. 12 is a detail of the door-shaft-operating means.

In the embodiment of my invention I have shown the double doors A A hung to swing in either direction and normally held closed and in the same plane by the spring 2 acting on the two arms 4, which are rigid with the door-shafts 5.

55 The arms and springs and the operating mechanism for opening and closing the doors

to be described are arranged beneath the floor.

The doors are fixed to their respective shafts 5, so as to turn in unison with them. 60 If desired, the shafts may be spring-supported in the doors to relieve shock, as in my former patent, No. 807,043, dated December 12, 1905.

On each side of the door-opening is a 65 hinged platform 6. These platforms are pivotally supported, as on the pivot-shaft 7, along their adjacent edges and are resiliently supported at their outer edges on the springs 8. Suitable mechanism constituting my invention is employed to open the doors simultaneously in one direction and away from one platform when that platform is depressed and to open the doors simultaneously in the opposite direction when the other platform is 75 depressed.

The opening of the doors in either direction is effected by a spring-motor, one arranged on each side of the door and adapted to be released on the depression of a platform and 80 to be reset ready for the next operation by an electric motor operating intermittently through the medium of the spring-motors.

Each spring-motor comprises a carriage 9, sliding on guides 10 and carrying two rods 11, 85 which support at their outer ends a cross-head 12. This cross-head slides in unison with carriage 9 on the fixed bar 13. A helical spring 14, surrounding bar 13, bears against the cross-head and against a fixed part 15 90 and tends normally to press the cross-head outward away from the door-opening.

Each carriage 9 carries a rack-bar 16, which is adapted to be engaged by a sliding pinion 17 on power-shaft 18, one bar 16 being 95 arranged above the pinion and the other below the pinion. Shaft 18 is operated intermittently from any suitable source of power, as an electric motor with suitable connections, as a belt passing over pulley 18' on 100 shaft 18.

When the pinion 17 is slid in between the bars 16 and rotated, one or the other of the bars will be reciprocated to compress a corresponding spring 14, as indicated at the right 105 of Figs. 1, 2. The two bars are cut-out, as shown at 19, Fig. 2, so that when one spring 14 is compressed and locked (by means of the knobs 20 on rods 11 and the locking-bar 21 in a manner to be described shortly) the other bar 16 may be engaged to pull in the expanded spring without the gear

17 interfering in any way with the other bar and its spring-operated mechanism.

Each spring-motor has a crosswise-extending lengthwise-movable locking-bar 21, having the perforations 22 23. The perforations 22 accommodate the guides 10, and the perforations 23 permit the rods 11 to have a free sliding movement through them under certain conditions, the holes 23 being enlarged 10 at one end to pass the knobs 20 on the rods 11. A spring 24, carried by each bar 21, acts on a guide 10 to press its bar 21 normally across the path of a pair of knobs 20 when its spring 14 is compressed, and so hold the 15 spring 14 under compression. To release the spring-motor and allow spring 14 to expand to open the door, the bar 21 is shifted to bring the enlargements of holes 23 into line with the knobs 20 by means later to be 20 described.

Each door-shaft 5 has in addition to arm 4 a rigid arm 25 and two loose arms 26, one above and one below arm 25. The upper loose arms 26 connect by links 27 with one 25 cross-head 12, and the lower loose arms 26 connect by similar links 27' with the other cross-head.

The links pivot a short distance from their ends to their respective arms 26, as at 28, and 30 have concaved heads 29, which are adapted when the doors are in closed position and a cross-head moved outward to engage behind a pin or projection 30 on the rigid arms 25 and open the doors in the proper manner.

35 It is understood that the shape and size of the heads 29 and their location with respect to their pivots 28 are such that with the doors in normally closed position and both springs 14 set arms 25 can turn with the doors in one 40 direction when engaged by the one pair of heads 29 without engaging or interfering with the other pair of heads 29. Vice versa, the doors may turn in the opposite direction without interfering with the first-mentioned 45 pair of heads. Thus while the heads are disposed when the doors are closed and the spring-motors set in such position that they will lie just outside the arc described by the arms 25 still a head 29 will describe such an 50 irregular curve when its cross-head moves outward that a pin 30 will be surely intercepted and a door-shaft turned.

When the doors are in a normally closed position, the arms 4 and springs 2 stand in line, and the cross-heads 12 are brought in close to the doors to compress the springs 14, and both motors are in set position.

When a cross-head is released and moved outward by the expansion of its spring 14 as 60 indicated at the left of Fig. 1, the links 27' and their corresponding connections operate on the door-shafts to open the doors toward the right, as indicated in that figure, the spring-motor on the right being unaffected 65 by the operation of the motor on the left.

When the other cross-head is released, the links 27 act to open the doors in a reverse direction.

The release of the spring-motor to open the doors is effected by the following means: 70 Each platform 6 has a downwardly-extending projection 33, which is adapted to operate a latch member 34, pivoted at 35, and having a hook portion to engage over a lever 36, which latter is fulcrumed at 37. Lever 75 36 is connected at one end to a spring 38, which tends constantly to move the lever 36 away from the latch member 34. As shown in Figs. 10, 11, a link 39 is hinged to the other end of lever 36 to swing in a vertical plane. 80 This link works through a slot 39' in a fixed plate 42 and has a hook 40 on its under side arranged to be engaged by a cross-head 12 when the latter is moved inward toward the doors to set its spring 14. The link 39 is 85 partly above and partly below plate 42, as shown in Fig. 10. The front wall of the slot 39' forms a support for the link to ride on. When the link is at its innermost position, or, what is the same thing, when lever 36 is set 90 as in Figs. 10, 11 and right of Fig. 1, an inclined part 41 on the under side of the link is adapted to ride up on the plate and lift the hook 40 out of the range of action of cross-head 12. However, when lever 36 is 95 released it pulls link 39 out and down, so that hook 40 can be engaged by cross-head 12 at the proper time. A spring 42' is fixed to the top of plate 42 and bears on the top of link 39 to depress the latter into proper engaging position with the cross-head. The function of link 39 is simply to reset lever 36 when spring 14 is being reset by means of the rack and pin 16 17.

The release of the lever 36 from its catch 34 105 has the effect of releasing its corresponding spring 14 and causing the doors to open. In Fig. 1 lever 36 at the right is shown as set. At the left of the same figure it is shown as released. When lever 36 is released, its spring 110 38 rocks it and causes a curved member 43 to engage and rock a lever 44, which latter is fulcrumed to a fixed part of the apparatus at 45. This lever 44 is adapted to engage a pin or projection 46 on a locking-bar 21 and to move 115 this locking-bar against the tension of its spring 24 and to bring the enlarged portions of the perforations 23 into line with the knobs 20. This results immediately in the release of the spring 14 at that side of the doors and 120 the opening of the doors accordingly.

After a spring 14 has been released, as shown at the left of Fig. 1, the cross-head 12 is moved beneath plate 42 and behind hook 40. When the cross-head is moved in again 125 in the act of compressing spring 14, the cross-head engages hook 40 and pulls lever 36 around against the tension of spring 38 until the lever is caught by the latch 34. As soon as latch 34 has caught the lever the link is 130

lifted by the incline 41 riding up on plate 42 to release the cross-head.

49 is a lever fulcrumed at 49' and spring-supported between its ends, as shown at 51. 5 It carries at its inner end a wedge segment or spreader 52, which is adapted when the lever is pressed down to embrace approximately one-half of shaft 18. The spreader 52 on one side of the apparatus, or on the left as here 10 shown, engages on top of shaft 18, while the spreader 52 on the other side of the apparatus engages on the under side of shaft 18.

As shown in Fig. 3, lever 49 on the right is made in two sections, jointed at 49^a to enable 15 its spring-support 51 normally to carry its spreader 52 downward from shaft 18. These spreaders 52 are movable into and out of engagement with the loose collar 54 and the fixed collar 56 on shaft 18 for the purpose of 20 withdrawing pinion 17 from between the racks 16, the pinion 17 being inserted between racks 16 through the medium of cams 55, as will be described. Pinion 17 is slideable on and turnable with shaft 18 and is connected by suitable means, as the two rods 53, 25 with the loose collar 54, which is slideable on and turnable with shaft 18. The rods 53 work in suitable longitudinally-extending grooves in shaft 18, so as not to interfere with 30 the turning movements of the complementary cams 55, which encircle and turn on the shaft between the gear 17 and collar 56. The latter is between the sliding collar 54 and cams 55 and is fixed to shaft 18. A spring 35 57 operates against the collars 54 56 to carry the pinion 17 normally out of engagement with either of the racks 16. On the opposite side of cams 55 or adjacent to pinion 17 is a helical spring 58, a little stiffer than spring 57, 40 but shorter than the maximum distance between cams 55 and pinion 17, so that with the cams in closed position, as shown in Fig. 7, the spring 58 will be relaxed. If, however, the cams 55 are turned with relation to one 45 another to open them out, as in Fig. 1, the innermost cam will engage a loose washer 59 on shaft 18, compress springs 58 57, and push gear 17 in between the racks 16. The purpose of spring 58 is to relieve shock to the apparatus and prevent breakage from the too 50 sudden operation of the parts. Each cam 55 has a projecting arm 60, and each arm is operated on by a respective spring 61 to carry the two cams into relatively closed position. 55 Each arm 60 connects by a link 62 with an arm 63 of a rock-shaft 64, which latter has two short arms 65 66.

When a spring-motor is released, its carriage 9 flies outward on its guides 10 and in 60 so doing engages near the end of its stroke an arm 65 to rock one of the cams 55 and open them out so as to compress spring 58 and push gear 17 at the proper moment in 65 between the racks 16. At the same time the outward movement of the cross-head 12

opens the doors in the manner previously indicated. The spreading apart of cams 55 sets the shaft 18 in operation by reason of the engagement of a spring-actuated bell-crank lever 67 in the path of the cams, lever 70 67 acting to close the circuit through wires 68, which connect with the motor 69.

When the arm 63 is rocked to spread the cams 55, the arm 66 engages behind a spring-stop 70 on lever 49 to hold the cams 55 in 75 spread position until the carriage 9 has been retracted and the knobs 20 reengaged behind its lock-bar 21. As the carriage is retracted it engages a stop 71 on lever 49, depresses the lever 49, and interposes its spreader 52 between the collars 54 56 and removes pinion 17 from between the racks 16 at the proper instant. The act of depressing lever 49 releases arm 66 from stop 70 and allows spring 61 to return cam 55 to normal closed 85 position with its neighbor.

When the spring-motor is reset by compressing its spring 14 and drawing in its cross-head 12, the loose arms 26 turn back on shafts 5 to initial position, leaving the 90 doors free to close by the agency of springs 21 and independent of the door-opening means. It is possible, however, that a person may not step off of one platform by the time that its spring-motor is reset, and some 95 means must be employed to prevent the immediate release again of the motor. Therefore I provide the bell-crank lever 72 to insure the locking of lever 36 by latch 34 even though the weight be still on the platform. 100 Lever 72 is pivoted to have both a horizontal and vertical turning movement, and one arm is adapted, through the medium of spring 73 and stop 74, to be normally interposed between projection 33 and latch 34. The 105 other arm is interposable in the path of a respective cross-head 12. As the doors approach full-open position the cross-head strikes lever 72, rocks it and removes it from between projection 33 and latch 34, resuming 110 its normally locked position with respect to lever 36 when the latter is pulled around eventually by the cross-head. So long as the weight remains on the platform, lever 72 cannot interpose itself between the projection 33 and latch 34, and as projection 33 is 115 so short that it can only act on latch 34 to release the cross-head when lever 72 is between the two the spring-motor cannot act until the platform lifts enough to let lever 120 72 assume once more its normal position.

The following means are provided to prevent both platforms being operated simultaneously, as in case two persons approaching from opposite directions should come 125 upon both platforms at the same time, or in case one person is on one platform and the doors are opening away from him and another person should come upon the other platform before the doors are fully opened. 130

Each platform carries near its outer edge two projections 75 and two projections 76, Figs. 1, 4, 5, 6, the projections 75 76 in each set on the two platforms being arranged in line 5 crosswise of the platform. Each projection 76 is adapted to operate a respective bell-crank lever 77, which is engageable with a respective collar 78 on a cross-rod 79. This cross-rod 79 is supported in suitable bearings 10, and the ends of the rod 79 carry blocks 81, interposable according to the direction in which the rod 79 is shifted by a bell-crank 77 into the path of a corresponding projection 75. Thus if one platform 6 is stepped 15 upon its projections 76 are depressed to kick their bell-cranks 77 and shift the rods 79 toward the opposite platform and interpose a set of blocks 81 under the projections 75 on said opposite platform. If the latter 20 platform should then be stepped upon it would not be depressed, since it would be held up by its blocks 81. The blocks 81 are held in normal inoperative position with respect to the projections 75 by means of the 25 springs 82, which press outwardly constantly in opposition to each other against the collars 78 on the rods 79.

As long as weight is on one platform the previously-described means are sufficient to 30 keep the other platform from being depressed; but inasmuch as a person going through the doorway will step from one platform to the other it is essential that the second platform be not allowed to sink until the doors start 35 to close. Hence it is that the following means are provided to temporarily check the withdrawal of one or the other sets of blocks 81 from beneath their respective projections 75.

A spring-actuated latch member 84 is arranged with respect to each block 81, as shown in Figs. 1, 5, 6. Normally with the blocks 81 in inoperative position between respective projections 75 the latches 84 will bear against the side of the respective blocks 45 81. The moment, however, that the rod is shifted to move a block 81 under its projection 75 the latch 84 will automatically project behind the block 81, as indicated in Fig. 6, and hold the rod 79 in opposition to the springs 50 82. This latch is retracted, however, as soon as the doors are fully opened by the engagement of a projection 85 on an arm 4 with a respective bell-crank lever 86. These levers 86 are suitably positioned relative to the arc 55 of movement of the arms 4. The rocking of a bell-crank lever 86 operates a rod 86', bell-crank lever 87, which has one arm connected with a latch member 84, and releases a block 81. The ends of rods 86' where they connect with levers 87 are slotted, as at 87', to permit the necessary movements of the levers 86 with respect to the arc of movement of projections 85. Springs 86^a act on rods 86' to hold levers 86 in proper operative position.

The operation of this part of the apparatus is as follows: When the platform 6 at the left is depressed, rods 79 are shifted to carry their blocks 81 at the right under the projections 75 of the right-hand platform to hold the latter up. The latch members 84 on the right spring in behind their blocks 81 and hold up the platform on the right as long as the doors remain open toward the right. When the doors close, the projections 85 encounter the bell-crank levers 86 and rock the levers 87 to retract the latches 84. Since the weight has been removed from the platform at the left, the rods 79 are free to act by reason of the tension of spring 82, and so carry the blocks 81 at the right out from beneath their projections 75 into initial neutral normal position. In order to permit two or more persons following single file to pass through the doors without having to wait for the spring-motor to be reset or the doors to close completely each time, I provide a plate 88 under each platform, each plate 88 having two upwardly-extending projections 89 95 arranged in the path of a respective cross-head and also having a wedge-shaped projection 90 adapted to be thrust under a respective projection 94 on the platform 6 when the cross-head moves outward. Each plate 88 is supported on a lever 49, (by the pin 91 working in a slot 92,) and the end 90 of the plate slides on a spring 93 on lever 49. When the cross-head is released from set position and the doors are opened, the wedge 90 is thrust under a projection 94 on the platform, the spring 93 giving sufficient for the purpose and resulting in holding a spreader 52 in position between the collars 54 56 and preventing gear 17 moving into engagement with either of the racks 16. As long as the weight 105 remains on the platform the spring 14 will remain expanded and the doors open, allowing a person to pass through. When the weight is taken off the platform, the spreader 52 lifts, allowing cams 55, which were expanded 110 when the doors opened, to push gear 17 into mesh with a rack 16. When the cam 55 was rocked to spread them and compress spring 58, the motor-circuit was closed and shaft 18 set in motion; but as long as the spreader 52 115 remained between collars 54 56 pinion 17 was inoperative. If after the weight is taken off of the platform and the doors have started to close and the electric motor has started to reset the spring-motor a second person should 120 instantly step on the same platform after the first person has stepped off of it, the spreader 52 will be pressed down again, throwing pinion 17 out of mesh with the rack 16 and allowing spring 14 to expand again and open 125 the doors. When the cross-head returns nearly to its initial set position, it engages projection 95 on plate 88 and withdraws it from beneath the platform projection 94.

While I have shown the invention applied 130

to double doors, it is manifest that it is equally applicable to a single swinging door.

Having thus described my invention, what I claim, and desire to secure by Letters Patent, is—

1. In door opening and closing apparatus, the combination of a pair of doors hung to swing in either direction, a spring-motor on each side of the door-opening, connections between one motor and the doors to open them in one direction, and connections between the other motor and the doors to open them in the opposite direction, and means to actuate the spring-motors.
2. In door opening and closing apparatus, the combination of a pair of doors hung to swing in either direction, a spring-motor on each side of the door-opening, connections between one motor and the doors to open them in one direction, and connections between the other motor and the doors to open them in the opposite direction, means to actuate the spring-motors independently, and means independent of the motors to close the doors.
3. In door opening and closing apparatus, the combination with a pair of doors hung to swing in either direction, a spring-motor on each side of the door-opening, connections between one motor and the doors to open the latter in one direction, and connections between the doors and the other motor to open the doors in the opposite direction, a movable platform on each side of the door-opening, and means for releasing each motor independently on the depression of its respective platform.
4. In door opening and closing apparatus, the combination with a pair of doors hung to swing in either direction, a spring-motor on each side of the door-opening, connections between one motor and the doors to open the latter in one direction, and connections between the doors and the other motor to open the doors in the opposite direction, a movable platform on each side of the door-opening, means for releasing each motor independently on the depression of its respective platform, and means for resetting a motor on the raising of its platform.
5. In door opening and closing apparatus, the combination with a pair of doors hung to swing in either direction, a spring-motor on each side of the door-opening, connections between the motors and doors to open the latter, means to reset the motors, hinged platforms and means operated by the platforms to release the motors.
6. In door opening and closing apparatus, the combination of a door, a spring-motor connected with the door to open the latter, means independent of the motor to close the door, means for setting said motor in position to open the door, and means to release the motor from its set position to open the door.

7. In door opening and closing apparatus, the combination of a pair of doors hung to swing in either direction, spring-motors connected with the doors to open the latter, a hinged platform on each side of the door-opening, and means operated through the platforms to actuate the motors.

8. In door opening and closing apparatus, the combination of a pair of doors hung to swing in either direction, spring-motors connected with the doors to open the latter, a hinged platform on each side of the door-opening, and means operated through the platforms to actuate the motors, said last-named means including an electric motor to reset the spring-motors.

9. In door opening and closing apparatus, the combination with a door, of a spring-actuated member connected with the door to turn the latter in one direction, means independent of said member to turn the door in the opposite direction, electrically-operating means to set and hold said member against the action of its spring, a hinged platform and suitable connections operated therethrough to release said member from its set position.

10. In door opening and closing apparatus, the combination with a door, of a spring-actuated member connected with the door to turn the latter in one direction, means independent of said member to turn the door in the opposite direction, electrically-operating means to set and hold said member against the action of its spring, a hinged platform and suitable connections operated therethrough to release said member from its set position, said setting means for said member including an intermittently-operated electric motor.

11. In door opening and closing apparatus, the combination with a door, of a spring-actuated member connected with the door to turn the latter, a rack-bar connected with said member, a pinion engageable with and disengageable from said rack-bar, means to engage the pinion with the bar, means to rotate the pinion to set the spring-actuated member against the tension of its spring, and means to lock said member in said set position.

12. In door opening and closing apparatus, the combination with a door, of a spring-actuated member connected with the door to turn the latter, a rack-bar connected with said member, a pinion engageable with and disengageable from said rack-bar, means to engage the pinion with the bar, means to rotate the pinion to set the spring-actuated member against the tension of its spring, means to lock said member in said set position, said means to rotate the pinion being electrically operated, and switch mechanism for said electrically-operated means operable synchronously with the engaging and disengaging movements of the pinion.

13. In door opening and closing apparatus, the combination of a door, a hinged platform, a spring-actuated part beneath the platform suitably connected with the door to open the door on the movement of said part in one direction, electrically-operated means for moving said part in the opposite direction to set it, and means for holding said part in said set operative position.
14. In door opening and closing apparatus, the combination of a door, a hinged platform, a spring-actuated part beneath the platform suitably connected with the door to open the door on the movement of said part in one direction, electrically-operated means for moving said part in the opposite direction to set it, means for holding said part in said set operative position, and means operative by the platform for setting said electrically-operated means in operation.
15. In a door opening and closing apparatus, the combination of a door, a hinged platform, a spring-actuated part beneath the platform suitably connected with the door, said part provided with a rack-bar portion, a pinion movable into and out of engagement with said rack-bar, means operative by the platform to move said pinion into and out of engagement with said rack-bar and means to operate the rack-bar.
16. In door opening and closing apparatus, the combination of a door, a hinged platform, a spring-actuated part connected with the door to open the latter, means independent of said part to close the door, means for holding said part in set position against the tension of its spring in readiness to open the door, means operated by the platform to release said part to open the door, electrically-operated means for resetting said part in readiness for the next operation, and detent means operable through the medium of the platform for holding said spring-actuated part in set position.
17. In door opening and closing apparatus, the combination of a door, a hinged platform, a spring-actuated part connected with the door to open the door, means independent of said spring-actuated part to close the door, said spring-actuated part having a rack-bar portion, a pinion intermittently engageable with the rack-bar to move the latter to set said spring-actuated part in operative position, means to move the pinion and electrically-operated means to rotate the pinion.
18. In door opening and closing means, the combination of a door, a hinged platform, a spring-actuated part connected with the door to turn the latter, a rack-bar portion connected with said spring-actuated part, a pinion to engage said rack-bar, means operative through the medium of the movements of the platform to move said pinion into and out of engagement with said rack-bar, means to rotate the pinion and means to prevent the engagement of said pinion with said rack-bar while the platform is depressed.
19. In door opening and closing apparatus, the combination of a pair of hinged doors mounted on suitable pivot-shafts, a hinged platform, a spring-actuated part beneath the platform suitably connected with the door to open the latter on the movement of said part in one direction, said connections including fast and loose arms on the respective pivot-shafts of said doors, and links connecting said loose arms with said spring-actuated part, means independent of the latter to close the door, and means to set said part in operative position in readiness to open the doors.
20. In door opening and closing apparatus, the combination of a door, a hinged platform, a spring-actuated part beneath the platform suitably connected with the door to open the latter on the movement of said part in one direction, spring means to move said part in said direction to open the door, a rack-bar connected with said part, a power-shaft, a pinion slideable on said shaft and engageable and disengageable with said rack-bar, means to effect the disengagement of said pinion with said rack-bar, means controlled by the movements of the platform to set said shaft in motion to move said spring-actuated part against the tension of its spring.
21. In door opening and closing apparatus, the combination of a door, a hinged platform, means beneath the platform and operative thereby to open the door in one direction, means independent of said opening means to close the door, said door-opening means including a spring-actuated part, a rack-bar connected therewith, a power-shaft, a pinion slideable on the shaft and engageable and disengageable with said rack-bar, means including a rockable cam on the shaft to move said pinion into engagement with said rack-bar and means to rotate the shaft.
22. In door opening and closing apparatus, the combination of a door, a hinged platform, means beneath the platform and operative thereby to open the door in one direction, means independent of said opening, means to close the door, said door-opening means including a spring-actuated part, a rack-bar connected therewith, a power-shaft, a pinion slideable on the shaft and engageable and disengageable with said rack-bar, means including a rockable cam on the shaft to move said pinion into engagement with said rack-bar, means to rotate the shaft, and means operative through the movement of the platform to control the engagement of said rack-bar.
23. In a door opening and closing apparatus, the combination of a pair of doors, a hinged platform, a spring-actuated part beneath the platform connected with the doors to open the latter on the movement of said part in one direction, a spring to effect said

- movement of said part to open the doors, a rack-bar connected with said part, a power-shaft, a pinion slideable on the shaft and engageable with the rack-bar, means to turn the 5 pinion to retract the bar to compress said spring, detent means to hold said spring-actuated part in set position against the tension of its spring, and means operative by the platform to release said detent means.
24. In a door opening and closing apparatus, the combination of a pair of doors, a hinged platform, a spring-actuated part beneath the platform connected with the doors to open the latter on the movement of said 10 part in one direction, a spring to effect said movement of said part to open the doors, a rack-bar connected with said part, a power-shaft, a pinion slideable on the shaft and engageable with the rack-bar, means to turn the 15 pinion to retract the bar to compress said spring, detent means to hold said spring-actuated part in set position against the tension of its spring, means operative by the platform to release said detent means, and means 20 controlled by the movements of the platform to govern the engagement of the pinion with said rack-bar.
25. In door opening and closing apparatus, the combination of a pair of doors, a hinged 25 platform on each side of the door-opening, a spring-actuated part under each platform suitably connected with the doors to open the latter, a spring to actuate each of said parts, each of said parts having rack-bar extensions, said extensions arranged parallel 30 with and suitably spaced from each other, a pinion operative between said rack-bars and engageable and disengageable therewith, and means whereby said pinion may be engaged 35 with one rack-bar to set its spring-actuated part without affecting the other rack-bar.
26. In door opening and closing apparatus, the combination of a pair of doors, a hinged platform on each side of the door-opening, a 40 spring-actuated part under each platform suitably connected with the doors to open the latter, a spring to actuate each of said parts, each of said parts having rack-bar extensions, said extensions arranged parallel with and 45 suitably spaced from each other, a pinion operative between said rack-bars and engageable and disengageable therewith, means whereby said pinion may be engaged with one rack-bar to set its spring-actuated part 50 without affecting the other rack-bar, means for locking said spring-actuated parts in set position, and means to release one of said 55 spring-actuated parts to open the doors in one direction, without affecting said other 60 spring-actuated part.
27. In door opening and closing apparatus, the combination of a pair of doors, a hinged platform on each side of the door-opening, a 65 spring-actuated part under each platform suitably connected with the doors to open
- the latter, a spring to actuate each of said parts, each of said parts having rack-bar extensions, said extensions arranged parallel and suitably spaced from each other, a pinion operative between said rack-bars and engageable and disengageable therewith, means whereby said pinion may be engaged with one rack-bar to set its spring-actuated part without affecting the other rack-bar, means for locking said spring-actuated parts in set 70 position, means to release one of said spring-actuated parts to open the doors in one direction without affecting said other spring-actuated part, and means controlled by the movements of the platforms to govern the engagement of said pinion with the respective rack-bars.
28. In door opening and closing apparatus, the combination of a pair of doors, a hinged platform, a spring-actuated part suitably 75 connected with the doors to open the latter, a spring to actuate said part, a rack-bar connected with said spring-actuated part, a power-shaft, a pinion slideable on the shaft and movable into and out of engagement 80 with said rack-bar, a loose collar on the shaft connected with said pinion, a fixed collar on the shaft between said pinion and said loose collar, means for carrying the pinion normally out of engagement with said rack-bar, a means including a rockable cam member 85 coöperating with said fixed collar to move said pinion into engagement with said rack-bar, and electrically-operated means to turn the shaft to set said spring-actuated part. 90
29. In door opening and closing apparatus, the combination of a pair of doors, a hinged platform, a spring-actuated part suitably connected with the doors to open the latter, a spring to actuate said part, a rack-bar connected with said spring-actuated part, a power-shaft, a pinion slideable on the shaft and movable into and out of engagement 95 with said rack-bar, a loose collar on the shaft connected with said pinion, a fixed collar on the shaft between said pinion and said loose collar, means for carrying the pinion normally out of engagement with said rack-bar, a means including a rockable cam member 100 coöperating with said fixed collar to move said pinion into engagement with said rack-bar, and electrically-operated means to turn the shaft to set said spring-actuated part. 105
30. In a door opening and closing apparatus, the combination of a pair of doors, a hinged platform on each side of the door-opening, a spring-actuated part under each 110 platform suitably connected with the doors to open the latter, a spring to actuate each of said parts, each of said parts having rack-bar extensions, said extensions arranged parallel with and 115 suitably spaced from each other, a pinion operative between said rack-bars and engageable and disengageable therewith, means whereby said pinion may be engaged with one rack-bar to set its spring-actuated part, and switch mechanism operative by the movements of said cam for controlling the operation of said electrically-operated means. 120
31. In a door opening and closing apparatus, the combination of a pair of doors, a hinged platform on each side of the door-opening, a spring-actuated part under each 125 platform suitably connected with the doors to open the latter, a spring to actuate each of said parts, each of said parts having rack-bar extensions, said extensions arranged parallel and suitably spaced from each other, a 130

pinion operative between said rack-bars and engageable and disengageable therewith, means whereby said pinion may be engaged with one rack-bar to set its spring-actuated part without affecting the other rack-bar, means for locking said spring-actuated parts in set position, means to release one of said spring-actuated parts to open the doors in one direction without affecting said other spring-actuated part, means controlled by the movements of the platforms to govern the engagement of said pinion with the respective rack-bars, and a device independent of said means

for maintaining the pinion normally out of engagement with said rack-bar, and operative by the movement of the platform to control the engagement of said pinion with said rack-bars. 15

In testimony whereof I have hereunto set my hand in presence of two subscribing witnesses. 20
